UNITED STATES PATENT OFFICE

146,003

DESIGN FOR A SPECTACLE FRAME

Louis Jacobson, New York, N. Y.

Application August 30, 1946, Serial No. 132,957

Term of patent 14 years

(Cl. D57—1)

To all whom it may concern:

Be it known that I, Louis Jacobson, a citizen of the United States and a resident of the county, city, and State of New York, have invented a new, original, and ornamental Design for a Spectacle Frame, of which the following is a specification, reference being had to the accompanying drawing, forming part thereof, wherein

Fig. 1 is a side elevational view of a spectacle frame, and

Fig. 2 is a top plan view thereof, showing the essential features of my design in full lines.

I claim:

The ornamental design for a spectacle frame, substantially as shown and described.

LOUIS JACOBSON.
